UNITED STATES PATENT OFFICE.

MAX STROHBACH, OF MAGDEBURG, GERMANY.

UMBRELLA OR SUNSHADE HOLDER FOR CYCLES.

SPECIFICATION forming part of Letters Patent No. 566,252, dated August 25, 1896.

Application filed April 30, 1895. Serial No. 547,640. (No model.)

To all whom it may concern:

Be it known that I, MAX STROHBACH, carriage-builder, of 5 Warthe, Magdeburg, in the Empire of Germany, have invented an

5 Improved Umbrella or Sunshade Holder for Cycles, Rowing-Boats, and other Vehicles, of which the following is a specification, reference being had therein to the accompanying drawings.

10 This invention relates to an apparatus for holding an umbrella or sunshade on a cycle, boat, or other vehicle; and it has for its object the ability to adjust the umbrella or sunshade in any desired position.

15 In the accompanying drawings, which illustrate my invention, Figure 1 is a view in front elevation of the apparatus, and Fig. 2 is a view in side elevation thereof.

Throughout both views similar parts are 20 marked with like letters of reference.

The apparatus consists, essentially, of a socket or holder *a*, adapted to receive the umbrella or sunshade. This socket or holder has a shank *a'*, terminating in a fork *a''*, which 25 is pivoted by pins or screw-bolts *b* to a boss *f*, which is mounted on a pin *g*, carried by one part of a clamp *c*, which is adapted to fix the apparatus to the cycle, boat, or other vehicle, the clamp, as shown, being adapted to be attached to the steering-handle bar *i* of a cycle. The clamp *c* is preferably made in two 30 parts hinged together, as shown, and is clamped to its support by means of a bolt *d*. The position of the socket or holder *a* with 35 respect to the boss *f* is fixed and determined by the set-screw *i'*, screwed in a snug *a''* on one side of the fork *a''* of the socket or holder *a*, and the position of the boss *f* with respect to the clamp *c* is fixed and determined by 40 means of the nut *h* on the free end of the pin *g*.

It will be seen that with this device the umbrella or sunshade can be caused to assume any desired inclination or position, as it can

be adjusted in two planes at right angles to one another, and, furthermore, the entire apparatus can be clamped to its support in any desired position relative thereto.

I wish it to be particularly understood that I do not limit myself to the precise details of construction hereinbefore described, and illustrated by the accompanying drawings, but that I hold myself at liberty to make such changes and alterations as fairly fall within the spirit and scope of my invention.

What I claim, and desire to secure by Letters Patent of the United States, is—

1. The umbrella-holder herein described consisting of a cylindrical clamp *c* for a horizontal bar, provided with an upwardly-projecting end threaded pivot *g*, a hub *f* mounted to turn on the pivot *g*, a clamp-nut *h* screwing on the pivot *g* against the hub *f*, threaded pivots *b*, projecting from opposite sides of the hub *f*, at right angles to the pivot *g*, a holder *a* having bifurcated ends pivoted 65 on the pivots *b*, and clamp-nuts screwing on the pivots *b* against said bifurcated ends.

2. The umbrella-holder herein described consisting of a clamp *c* provided with an upwardly-projecting pivot *g*, a hub *f* mounted 70 to turn on the pivot *g* and carrying opposite pivots *b* at right angles to the pivot *g* and having a conical bearing around one pivot *b*, a clamp-nut screwing on the pivot *g* against the hub *f*, a holder *a* having bifurcated ends 75 pivoted on the pivots *b* and a boss on its side, and a binding-screw working in said boss against said conical bearing on the holder obliquely to the pivot *f*.

In witness whereof I have hereunto set my 80 hand in presence of two witnesses.

MAX STROHBACH.
